United States Patent Office

Des. 187,476
Patented Mar. 22, 1960

187,476

GAME DEVICE

Gabor Racy, New Haven, Conn.

Application May 1, 1959, Serial No. 55,745

Term of patent 14 years

(Cl. D34—5)

Fig. 1.

Fig. 2.

Fig. 3.

Fig. 1 is a perspective view illustrating a game device embodying my new design;

Fig. 2 is a side elevational view of the game device; and

Fig. 3 is a top plan view of the same.

I claim:

The new and ornamental design for a game device, substantially as shown.
